The ornamental design for a laboratory well plate as shown and described.

DESCRIPTION

FIG. 1 is an enlarged cross-sectional view of area 1 shown in FIG. 2 of a laboratory well plate showing our new design; FIG. 2 is a cross-sectional view thereof from line 2-2 in FIG. 4;

FIG. 3 is a an enlarged view of area 3 shown in FIG. 4; FIG. 4 is a top plan view thereof;

FIG. 5 is an enlarged cross-sectional view thereof taken from area 5 in FIG. 6; and,

FIG. 6 is a cross-sectional view thereof taken from line 6-6 in FIG. 4.

The broken lines in the Figures depict portions of the laboratory well plate that form no part of the claimed design.
